UNITED STATES PATENT OFFICE.

RALPH A. VINE, OF PHILADELPHIA, PENNSYLVANIA. ASSIGNOR TO UNION SPECIAL MACHINE COMPANY, OF CHICAGO, ILLINOIS, A CORPORATION OF ILLINOIS.

GUIDE FOR SEWING-MACHINES.

1,285,422

Specification of Letters Patent. Patented Nov. 19, 1918.

Application filed December 3, 1916. Serial No. 304,876.

To all whom it may concern:

Be it known that I, RALPH A. VINE, a citizen of the United States, residing at Philadelphia, in the county of Philadelphia, State of Pennsylvania, have invented certain new and useful improvements in Guides for Sewing-Machines, of which the following is a description, reference being had to the accompanying drawing, and to the figures of reference marked thereon.

The invention relates to new and useful improvements in guides for sewing machines, and more particularly to the means for holding the guide in operative position and for releasing said guide so that it may be moved to inoperative position.

An object of the invention is to provide a means for holding the guide in normal operative position, which means can be released by pressure of the hand of the operator in a direction which will turn the guide after the same is released to inoperative position.

In the drawings, which show by way of illustration one embodiment of the invention,

Figure 1 is a front view of a sewing machine having my improvement applied thereto;

Fig. 2 is a side view of the guide and its supporting means, also showing parts of the sewing machine;

Fig. 3 is a detail in perspective showing the means for holding the guide in operative position, and also the means for releasing the guide.

I have shown my invention as applied to a sewing machine of the well-known "cup feed" type wherein the fabric is supported by feed wheels during the stitching of the same. Said machine consists of a main casing 1, which supports two feed wheels 2 and 3. These feed wheels are of the usual character and may be positively driven. The fabric F to be stitched is supported between the feed wheels, the upper edges thereof project slightly above said feed wheels, so that the needle may pass through said edges and the edges of the fabric be covered by the looper threads. In Fig. 1 of the drawings I have shown the looper 4 of the stitch forming mechanism.

The present invention is directed wholly to the guiding devices for the fabric and the means for supporting said guiding devices in operative position and for releasing said

guiding devices. In the drawings I have shown a fabric guide which consists of a center plate 5, and side members 6 and 7 which are pivotally supported by said center plate. A spring 8 normally separates the upper ends of the side members 6 and 7 and presses the lower ends toward the fabric. Limiting thumb nuts 9 are provided for gaging the distance between the center plate and the side members 6 and 7. This center plate has a forwardly projecting nose 10 and the side members are also formed with forwardly projecting parts 11. These parts are so shaped and positioned that the two layers of fabric to be joined may be fed along the respective sides of the center plate and held thereagainst by the side members 6 and 7.

These members not only guide the layers of fabric to the feed wheels 2 and 3, but also serve to uncurl the edges of the fabric. This guiding device *per se* forms no part of the present invention. This guiding device is pivotally supported by a bracket 12, which, in turn, is fixed to the main casing 1 of the sewing machine. Said guiding device is pivotally connected to the bracket by a pivot bolt 13 which passes through the center plate and the bracket 12. Said bracket carries a head 14. The center plate has a forwardly projecting arm 15 on which is pivoted a latch 16. This latch is adapted to engage a notch 17 in the head 14, when the guide is in normally operative position, and the latch holds the guide in this position. When the guiding device is swung to inoperative position, as shown in dotted lines in Fig. 1, the latch 16 engages the head 14 in rear of the shoulder 18, which holds the guiding device in this position.

A spring 19 forces the latch into contact with the head 14. When it is desired to release the guiding device, the operator heretofore has been required to press on the latch 16 to withdraw the same from the notch 17, and the pressure on the latch for this purpose is in a direction opposite to the direction in which the guide must be turned in order to swing it to inoperative position and, therefore, the operator was also required to grasp the guide itself at the rear side thereof at the same time the latch is withdrawn in order to swing the guiding device to inoperative position. I have, therefore, provided an improved latch releasing device which may also be utilized for swinging the

guide to inoperative position. This latch releasing device as herein shown, consists of an arm 20, which is pivoted at 21 to the center plate of the guiding device. This arm is formed with a slot 22 which is adapted to engage a pin 23 on the latch 16. This slot 22 is formed eccentrically relative to the pivotal point of the arm 20. The slot is also so disposed that when the arm 20 is raised, 10 said slot engaging the pin 23 will force the latch at its lower end inwardly, thus withdrawing the latch from the notch in the head on the supporting bracket.

A movement of the arm in the direction 15 of the arrow in Fig. 1 will operate first to release the latch from the notch 17. A continued pressure on the lever in the direction of the arrow will swing the guiding device to the dotted line position. It will, 20 therefore, be seen that I have provided a releasing means for the latch which is pressed in the direction that the guiding device swings when moving to inoperative position, and, therefore, the operator merely 25 by pressing on the arm 20 may unlock the guiding device, and also move said guiding device to inoperative position.

From the above it will be apparent that I have provided means for positively holding 30 the guide in operative position, and also means which operates first to withdraw the latch and subsequently to move the guide after it is released to inoperative position. It will also be obvious that I have used the 35 term "inoperative" as defining any position of the guide other than that where the same operates to guide the fabric.

It will be obvious that minor changes in 40 the details of construction and the arrangement of parts may be made without departing from the spirit of the invention, as set forth in the appended claims.

Having thus described my invention what I claim is:

45 1. The combination of a fabric guide located in advance of the stitching mechanism, and adapted to be moved away from the stitching mechanism to inoperative position, means for holding said guiding device in 50 normal operative position, an arm movable relative to the guiding device for swinging

said guiding device to inoperative position, said arm having means for releasing the holding means for the guide.

2. The combination of a fabric guide located in advance of the stitching mechanism, and adapted to be moved away from the stitching mechanism to inoperative position, means for holding said guiding device in normal operative position, a pivoted arm for swinging said guide to inoperative position, said arm having means operable when the arm is swung in the direction of the movement of the guide for releasing the holding means.

3. The combination of a fabric guide located in advance of the stitching mechanism, and adapted to be moved away from the stitching mechanism to inoperative position, a pivoted latch for holding said guide in normal operative position, and means for moving said guide to inoperative position, including devices for releasing the latch prior to the moving of the guide.

4. The combination of a fabric guide located in advance of the stitching mechanism, and adapted to be moved away from the stitching mechanism to inoperative position, a pivoted latch for holding said guide in normal operative position, a pivoted arm, and devices between said pivoted arm and latch whereby the first movement of the arm in the direction of the movement of the guide to inoperative position will release the latch.

5. The combination of a fabric guide located in advance of the stitching mechanism, and adapted to be moved away from the stitching mechanism to inoperative position, a pivoted latch for holding said guide in normal operative position, a pivoted arm on said guide, and having a slot therein, and a pin carried by the latch and engaging said slot, being so disposed that a movement of the arm in a direction for swinging the guide to inoperative position will release the latch.

In testimony whereof, I affix my signature in the presence of two witnesses.

RALPH A. VINE
